MOP STRUCTURE

John Charles Trindl, Chicago, Ill.

Application May 22, 1943, Serial No. 488,032

3 Claims. (Cl. 15—153)

My invention relates to mop structures of the type in which a mop element composed of an assembly of comparatively short length cotton yarn or other suitable fabric is secured to a holder, the general object of the invention being to produce a simplified but more efficient mop structure which may be economically manufactured.

More in detail, one important object of the invention is to eliminate metal parts and to construct the mop holder of two non-metallic parts, preferably of wood, between which the mop element is clamped and which are held together in clamping engagement by ordinary stock screws readily accessible for removal and separation of the clamping parts so that a worn out mop element may be readily removed and replaced by a fresh mop element.

A further important object is to produce a mop structure in which the holder comprises a body having a longitudinally extending channel in its under side for receiving a clamping member in the form of a rod or bar between which and the body the mop element is clamped.

Another important object is to provide a rigid holder whose bottom presents a transversely rounded or convexed pressing surface which will efficiently co-operate with the surface of an expressing element to function substantially like a wringer roll for expressing water out of the mop element.

Another important object is to roughen the bottom of the holder, as by recessing or grooving, to provide ridges or edges for engaging the mop strands at several points along their lengths to distribute the tension thereon when the mop structure is applied to a floor during a cleaning operation or when the structure is applied to an expressing element, thus to prevent localization of tension on the strands at their points of connection with the holder and prolonging the life of the mop element.

A further important object is to provide a unitary mop element in which the mop forming strands are secured together by cross-wise stitching, which may be reinforced by tape, and with the width of the stitching area such that this area will extend transversely the full distance between the holder body and bar to receive the clamping pressure when the body and bar are secured together, this stitching and reinforcing area then serving as a guiding means for accurate application of the mop element to the holder.

The above enumerated and other important features of my invention are embodied in the

structure shown on the drawings, in which drawings:

Figure 1 is a perspective view of the mop structure;

5 Figure 2 is an end view;

Figure 3 is a section on plane III—III of Figure 1 showing the mop structure applied to a wringing or moisture expressing device;

10 Figure 4 is a plan view of a portion of the mop unit;

Figure 5 is a perspective view, partly in section;

Figure 6 is a perspective view, partly in section, showing a modified arrangement;

15 Figure 7 is a transverse section showing another modified arrangement;

Figure 8 shows the mop structure after cleaning and rinsing thereof;

Figure 9 shows the first application of the mop structure to a modified expressing element;

20 Figure 10 shows the structure rocked or rolled in one direction on the expressing element; and

Figure 11 shows the structure rocked or rolled in the opposite direction on the expressing element.

25 Referring to Figures 1 to 5, M indicates the mop element and H the holder element. The holder comprises the body 10 and a clamping bar 11. The body 10 is of non-metallic material, such as wood, and in its rear side has the opening 12 for receiving a handle structure P. In its under side and adjacent to its forward edge, the body has the comparatively large semi-circular channel 13 for receiving the bar 11 which is shown as being cylindrical and which is preferably of wood. The body has two or more holes 14 for ordinary stock screws 15 for threading into the clamping bar 11 to hold this bar in clamping position.

30 The mop element M is composed of a row or superposed rows of comparatively short strands or cords 16, preferably of material such as cotton, and these strands, along an area intermediate their ends, are secured together by cross-stitching 17 as shown on Figure 4, the width of this cross-

45 stitched area being such that, when the mop element is applied to the holder, the stitched area will extend transversely along the full distance of the semi-cylindrical surface of the channel 13. This stitched area may be reinforced on opposite sides by tape bands 18 and 19, these tape bands being of the same width as the stitching area and being secured by the stitching.

50 Referring to Figures 1 to 5, the clamping bar 11 is cylindrical and has its surface roughened as by corrugating or grooving to provide ridges or

edges 20 and recesses 21. When the structure is to be assembled, the mop element M is applied around the clamping bar with its tape reinforced stitched area in alignment with the bar, and then the holder body 10 is applied over this taped area and the screws 15 are inserted and secured to draw the clamping bar toward the body for clamping of the mop element. The clamping pressure of the bar against the body causes the mop material to engage around the corrugation ridges 20 and into the grooves 21 so that the mop element will be rigidly anchored along its taped area against transverse and longitudinal displacement on the holder. The bottom of the holder body 10, rearwardly of the channel 13, may also be roughened as by grooves 22.

With the lower half of the cylindrical clamping bar 11 projecting from the holder body 10, the holder bottom presents a generally transversely rounded or convexed pressing surface which is roughened as by the grooves or recesses 21 and 22. As the mop structure is moved back and forth under pressure over a floor to be cleaned, and the mop strands are dragged along the floor, the edges or ridges formed by the grooves will engage the strands at several points along their lengths to get a good grip thereon and distribute the pressure thereon to prevent localization of tension on the strands at their points of connection with the holder.

The curved roughened bottom of the holder also effects more thorough wringing and drying of the mop element when applied to a moisture expressing element after the mop has been dipped and rinsed. Referring to Figure 3, 23 indicates a wringing or moisture expressing pan of U cross-section which, in practice, is usually supported across the upper edge of a container, such as a pail, which contains the cleaning fluid such as water, the pan having the drain openings 24. When the mop has been rinsed, the structure is applied in the forward end of the pan substantially in the position indicated by Figure 2, the holder is then pressed down by its handle P to exert pressure against the mop strands between the pan and the holder and part of the moisture is expressed therefrom. The mop structure is then rocked or rolled by its handle along the bottom of and against the outer wall of the pan, as shown on Figure 3. During such rocking or rolling motion, the edges or ridges of the recesses 21 in the clamping bar 11 will engage with the mop strands at several points along their lengths to distribute the tension thereon to prevent localization of the tension at the points of connection of the strands with the holder as the strands are dragged along the pan during rocking or rolling of the holder. During the end of the rocking or rolling movement, the edges of the recesses 22 in the holder body will come into engagement with the strands to rip them while the ends of the strands are pressed against the forward wall of the pan during the final rocking movement of the holder. The mop is thus efficiently expressed and dried, with comparatively little effort on the part of the mop user. The distribution of the tension of the mop strands by the edges of the roughened bottom of the holder will minimize tearing of the strands from the holder and the life of the mop element is thus materially prolonged.

The modified structure of Figure 6 is the same as that of Figures 1 to 5 except that the roughened surface on the clamping bar is provided by spirally extending grooves 35.

In the modified arrangement of Figure 7, the holder body 10 has a transversely rounded or convexed bottom surface, and the channel 36 of rectangular cross-section for receiving a clamping bar 27 of rectangular cross-section, the height of the bar being such that, when the mop element is clamped into place in the holder body by securing of the screws 15, the bottom surface of the bar will be in alignment with the bottom surface of the holder body.

It will be noted that the cords X of the mop depending from the front of the clamping bar are longer than the cords Y depending from the rear of the bar. These relative lengths are such that, when the mop structure is being applied to the expressing pan 24, as shown in Figure 3, the ends of the cords are pressed against the side wall of the pan but do not extend beyond the upper edge of the side wall or beyond the upper rear edge of the holder body, so that the fluid will be driven from the ends of the cords or strands to assure effective drying.

Figure 8 shows the mop structure just lifted out of a pail after cleaning and rinsing thereof for application to a modified form of an expressing element shown in Figures 9, 10 and 11. This expressing element is of L shape comprising the legs 25 and 26. The expressing element is supported on the edge of a pail with the longer leg 25 inclining downwardly toward the pail center and with the leg 26 at the inner edge of the leg 25. The leg 25 has longitudinally extending channels 27 interconnected by cross channels 28, and the leg 26 has the longitudinally extending channels 29 connected by cross channels 30, through which channels moisture expressed from the mop element may flow into the pail. After withdrawal from the pail, the mop structure is applied downwardly under pressure against the expresser element leg 25, with the handle P extending substantially vertically. During this application of the structure to the expresser, the forward cluster of strands X will fold outwardly between the front face of the holder and the compressor leg 26 and then inwardly between the expresser bottom 25 and the holder, while the outer cluster Y of the strands will fold outwardly and then inwardly between the expresser bottom and the holder, the downward pressure on the handle causing the holder to move down the inclined bottom of the expresser toward the leg 26 thereof so that the strand cluster X is compressed for expression of moisture therefrom. After such downward pressure on the holder, it is rocked or rolled clockwise by its handle, as indicated by Figure 10, and during such rolling motion, the roughened surfaces of the clamping bar 11 engages the strands of the cluster X and drags them across the edges of the longitudinal channels 29 in the expresser bottom to thus force the moisture therefrom, while during the end portion of the rolling movement, the edges of the grooves 22 in the heel of the holder engage with the strands Y to force them against the expresser bottom and the edges of the channels 27, thus drying these strands. The holder may now be rocked in the opposite direction, as indicated by Figure 11, to drag the strands of the cluster X against and forwardly along the expresser bottom and the channels 27 for final drying of the large strand cluster X. The back and forth rocking or rolling movement of the holder may be continued although usually one forward and back rolling movement will be sufficient to effectively dry the mop element.

I have thus produced a practical and efficient mop structure which may be economically manufactured out of inexpensive available material and from which a used-up mop element may be readily removed by the housewife and a fresh element applied with accuracy. With the shape and construction shown, involving the transversely rounded or convexed holder body, the structure adapts itself readily to various types of expresser elements for efficient wringing and drying, the roughening of the holder bottom augmenting the efficiency of the mop structure when used on a floor and the efficiency of the wringing or drying operation besides prolonging the life of the mop element.

I have shown a practical and efficient embodiment of the features of my invention but I do not desire to be limited to the exact structure and arrangement shown and described as changes and modifications may be made without departing from the scope of the invention.

I claim as follows:

1. A mop structure comprising an oblong body having a wide channel in its underside extending longitudinally along the front portion thereof to leave an extended heel portion, a cylindrical clamping bar having its upper portion fitting into said channel and its lower portion exposed below the underside of said body, a stranded mop element having an intermediate portion thereof engaging around the upper portion of said bar with the strands depending therefrom, securing means for drawing said bar into said channel for clamping the intermediate portion of the mop element between the bar and the body, said exposed lower portion of said bar providing a rounded rocker fulcrum for said body whereby said body may be rocked for the application of pressure by said heel portion against the mop element when said mop element is moved along a surface to be cleaned or while being applied to an expressing element, said heel portion having longitudinally extending grooves in the bottom thereof providing longitudinally extending gripping edges for gripping the mop element strands at various points along their length whereby to distribute the tension on the mop element strands and prevent localization of the tension at the points of connection of the strands with the body to thereby eliminate tearing of the strands and to prolong the life of the mop element.

2. A mop structure comprising an oblong body having a wide semi-cylindrical channel in its under side extending longitudinally along the front portion thereof to leave an extended heel portion rearwardly of the channel, a cylindrical clamping bar for fitting into said channel with

its lower half projecting below the bottom of the body, a mop element having its intermediate portion engaging around the top of said bar with its strands extending therefrom, said bar being corrugated to provide longitudinally extending gripping edges, means for drawing said bar into the channel for engagement of the top gripping edges on the bar with the intermediate portion of the mop element for securing the mop element to the body, the underside of said heel portion being corrugated to provide longitudinally extending gripping edges, the gripping edges on said body and on the projecting portion of said bar serving to grip the mop element strands at various points along their length when said strands are being dragged along the surface to be mopped or when said body is rocked rearwardly while being applied to an expressing element, whereby to distribute the tension on the strands and to prevent localization of the tension at the points of connection of the strands with the body and to thereby prolong the life of the mop element.

3. A mop structure comprising an oblong body having a wide semi-cylindrical channel in its under side extending longitudinally along the front portion thereof to leave an extended heel portion rearwardly of the channel, a cylindrical clamping bar for fitting into said channel with its lower half projecting below the bottom of the body, a mop element having its intermediate portion engaging around the top of said bar with its strands extending therefrom, said bar being corrugated to provide longitudinally extending gripping edges, means for drawing said bar into the channel for engagement of the top gripping edges on the bar with the intermediate portion of the mop element for securing the mop element to the body, the under side of said heel portion being corrugated to provide longitudinally extending gripping edges on said body and on the projecting portions of said bar serving to grip the mop element strands at various points along their length when the strands are moved along a surface to be cleaned whereby to distribute the tension on the strands and prevent localization of the tension at the points of connection of the strands with the body, the strands extending from the forward side of said bar being sufficiently longer than the strands extending from the rearward side of the bar whereby when said body is moved forwardly and rocked rearwardly under pressure against a surface the ends of the strands will be pressed between the surface and the rear side of said heel portion for extraction of moisture from the strand ends.

JOHN CHARLES TRINDL.
